UNITED STATES PATENT OFFICE.

THURMAN J. MICHENER, OF CHARLEROI, PENNSYLVANIA.

TOY.

1,023,324.

Specification of Letters Patent.

Patented Apr. 16, 1912.

Application filed February 15, 1911. Serial No. 608,861.

To all whom it may concern:

Be it known that I, THURMAN J. MICHENER, citizen of the United States, residing at Charleroi, in the county of Washington 5 and State of Pennsylvania, have invented certain new and useful Improvements in Toys, of which the following is a specification.

This invention relates to improvements 10 in toys and has for its object to provide a toy flying machine which will propel itself on a stretched string or cable.

With the above and other objects in view, I have invented the toy illustrated in the 15 accompanying drawings, in which,

Figure 1 is a side elevation of my improved toy, Fig. 2 is a rear end elevation thereof, Fig. 3 is a view similar to Fig. 1 showing the car in longitudinal vertical section, and Fig. 4 is a top plan view of the device.

Referring to the accompanying drawings 1 indicates a car mounted on a pair of centrally disposed grooved rollers or wheels 2 25 and 3, each of which are secured to the car by means of depending members 4 and 5, which come together at their bottom ends and have secured thereto a weighted member 6 which is adapted to hold the car in 30 proper vertical position on the cable 7. The member 6 is provided with planes 8 and 9 one on either side thereof. Mounted on the outer ends of the axles 10 and 11 are propeller wheels 12 and 13, and mounted on an 35 axle 14 are a pair of propeller wheels 15. The axle 14 is journaled into the side of the car and located under the seat 16, and a wheel 17 fixedly mounted on the axle 14 engages and is revolved by the wheel 2. The revolution of 40 this wheel causes the revolution of the propeller wheels 15. The wheel 2 is fixedly mounted on the axle 10 and a spring 18 is also mounted on this axle 10, one of its ends being secured to the member 2 and the other 45 end being fixed to the member 4. One end of the axle 10 has a crank handle 19 thereon, which is adapted to wind up the spring 18. A member 20 is adapted to engage the

notches 21 in the wheel 12 and lock it against 50 rotation until it is desired to start the device. Planes 22 and 23 are attached to the sides of the car and a propeller 24 is secured to the front end thereof.

When the device is wound up and allowed 55 to operate on a fine wire cable it will present a very realistic appearance as all of the propeller wheels will be operating at one time; the wheel 24 by contact with the air and the others by means of the rotation of the axles upon which they are mounted. 60 The wheels 15 will revolve in a direction opposite to that of the wheels 12 and 13 adding to the effect presented by the toy.

I claim and desire to secure by Letters 65 Patent,

1. A toy comprising a car mounted on centrally disposed grooved wheels, means for causing the rotation of said wheels, and bladed wheels mounted on the ends of the axles bearing said grooved wheels. 70

2. A toy comprising a car mounted on centrally disposed grooved wheels, means for causing the rotation of said wheels, bladed wheels mounted on the ends of the axles bearing said grooved wheels, and 75 means for balancing said car upon a suspended cable.

3. A toy comprising a car mounted on centrally disposed grooved wheels, means for causing the rotation of said wheels, 80 bladed wheels mounted on the ends of the axles bearing said grooved wheels, means for balancing said car upon a suspended cable, an axle mounted on said car above one of said grooved wheels. 85

4. A toy comprising a car mounted on centrally disposed grooved wheels, means for causing the rotation of said wheels, bladed wheels mounted on the ends of the axles bearing said grooved wheels, means for 90 balancing said car on a suspended cable, an axle mounted on said car above one of the grooved wheels, a wheel fixedly mounted on said axle, and adapted to engage the grooved wheel thereunder. 95

5. A toy comprising a car mounted on

centrally disposed grooved wheels, means
for causing the rotation of said wheels,
bladed wheels mounted on the ends of the
axles bearing said grooved wheels, means
5 for balancing said car on a suspended cable,
an axle mounted on said car above one of
the grooved wheels, a wheel fixedly mounted
on said axle, and adapted to engage the

grooved wheel thereunder, bladed wheels
mounted on the ends of said axle.

In testimony whereof I affix my signature
in presence of two witnesses.

THURMAN J. MICHENER.
